ALFRED E. SANDOZ, OF NEWARK, NEW JERSEY

HAND BINDING TOOL

Application filed December 17, 1927. Serial No. 240,678.

This invention relates to a novel hand tool for attaching metallic corner decorations to leather card-cases, bill-folds, portfolios, memorandum books and similar articles.

- 5 The invention has for its principal object to provide a novel, simple, efficient and easily manipulated tool for the purposes above mentioned, whereby decorative corner elements may be applied and fastened to the
 10 desired article by retail dealers or others without necessity for the exercise of any especial skill, and so that retail dealers in leather or similar articles may offer to their customers a choice from a variety of such
 15 decorative elements and therefrom attach the chosen elements to the article purchased.
 Other objects of this invention, not at this time more particularly enumerated, will be clearly understood from the following description of the same.

The novel tool of this invention is clearly illustrated in the accompanying drawings, in which:—

- Fig. 1 is a side elevation of the tool made
 25 according to and embodying the principles of the invention; Fig. 2 is a top plan view of the same, with portions of the handle or lever members broken away; Fig. 3 is a front end elevation of the tool; Fig. 4 is a vertical longitudinal section, taken on line 4—4 in said Fig. 2; Fig. 5 is a view similar to that of Fig. 4, but illustrating the tool when performing its function; Fig. 6, is a detail horizontal section taken on line 6—6 in Fig.
 30 4; Fig. 7 is a detail horizontal section taken on line 7—7 in Fig. 5; Fig. 8 is a horizontal section taken on line 8—8 in Fig. 4; Fig. 9 is a view similar to that shown in Fig. 8 but with the adjustable shim-plates removed;
 35 Fig. 10 is a perspective view of the corner setting-plate of the tool; Fig. 11 is a perspective view of one of the shim-plates of the tool; and Fig. 12 is a perspective view of one form of corner ornament for the applying of which the tool is adapted.

Similar characters of reference are employed in all of the hereinabove described views, to indicate corresponding parts.

- Referring now to said drawings, the reference character 15 indicates the bottom jaw

member and 16 the top jaw member of the tool. The handles or lever members 17 and 18 are pivotally interconnected in crossed relation by a center pivot pin 19. The handle or lever member 17 is provided with a bifurcated end 17' which embraces and is pivotally engaged with said bottom jaw member 15 by a pivot member 20, and, in like manner, the handle or lever member 18 is provided with a bifurcated end 18' which straddles a guiding cross pin 22 with which said handle or lever member 18 is provided, and said top jaw member 16 is provided with a similar bifurcated rear end portion 16' which straddles a guiding cross pin 23 with which said handle or lever member 17 is provided. The interconnected arrangement of said jaw members and handle or lever members, as thus above set forth, is such as is calculated to produce a parallel movement of said jaw members toward and away from each other when the tool is manipulated, all in a manner well known to those familiar with parallel action pinchers, pliers and similar tools, and which per se is not claimed as new except in combination with the operative elements of the instant tool which are connected with and carried by the respective jaw members.

Carried by said bottom jaw member 15 is a work supporting table or plate 24. Secured by screws 25 or other suitable fastening means, to the inner or rearward end portion of said table or plate 24 is a housing formed by laterally spaced apart guide-pieces 26 and a covering keeper plate 27, which together form a longitudinal guideway or slideway 28. Mounted in said slideway 28 for limited backward and forward movement therein is a corner setting plate 29. To limit the movement of this corner setting plate 29 suitable stops are provided. Preferably these stops comprise indented portions 30 of predetermined length formed in the longitudinal marginal portions of said corner setting plate 29, into which in-

mented portions extend stop-lugs 31 with which said guide-pieces 26 are provided. Arranged between each stop-lug 31 and the rearward end of each indented portion 30 are compression springs 32, which serve to thrust said corner setting plate 29 rearwardly to its normal retracted position as determined by the engagement of the forward ends of said indented portions 30 with 10 said stop-lugs 31, all as shown more especially in Figs. 6 and 7 of the drawings. The forward end of said housing and the forward end of said corner setting plate 29 are V-shaped having diverging portions 33 15 including an angle of 90 degrees so as to conform to the corner of an article supported on the table or plate 24 in opposition thereto. Secured to the top jaw member is a bridge piece 34 to the respective opposite 20 sides of which are affixed depending cam-rods 35 having at their lower ends chamfered cam-portions 36 to engage the rearwardly projecting end of said corner setting plate 29.

25 The reference character 37 indicates a carrier block having rear side faces 37' converging at right angles and aligned to the V-shape corresponding to the corner of an article supported on the table or plate 24.

30 The upper end of said carrier block is provided with a central longitudinal rib 38 to define the inner boundaries of longitudinal guideways 39 on each side thereof in which are slidably disposed shim plates 40, the 35 opposite sides of the respective guideways being formed by bosses 41 with which the upper end of said carrier block is provided. Formed in each rear side face 37' of said carrier block is a vertical slideway 42 having undercut sides, and in which are slidably disposed the slide-shoes 43 of punch- 40 plates 44 and 45. Said punch plates are individually capable of a limited vertical movement relative to said carrier block for 45 purposes of adjustment as will be herein-after more fully explained, and to such end keeper screws 46 are passed through vertical slots 47 in said punch plates and screwed into the body of said carrier block.

50 Disposed over the upper end of said carrier block 37 and overhanging the rear side faces 37' thereof so as to form an abutment for the upper ends of said punch plates 44 and 55 45 is a keeper plate 48, which also closes over the guideways 39 of said shim plates 40. Said keeper plate is retained in proper assembled relation to said carrier block by 60 dowel pins 49 or in any other suitable or convenient manner. Yieldably supported in connection with the underside of said carrier block is a clamp plate 50. This clamp plate is suspended from the carrier block by screws 51 the heads of which are counter-sunk in the carrier block body with the

shanks extending slidably and downwardly therethrough and into threaded connection with the clamp plate, compression springs 52 being arranged around the screw shanks between the underside of the carrier block 70 and said clamp plate, thus mounting the clamp plate for upward yielding movement. The clamp plate 50 may be provided on its under side with a facing 53 of leather or any other relatively non-abrasive material. Additional compression springs 54 may be suitably arranged between the clamp plate 50 and carrier block 37 as shown in the drawings if it is so desired. The carrier block 37, with the parts assembled in connection therewith in the manner above described, is secured to the under side of the top jaw member so as to move therewith; one convenient method of operatively connecting the same together comprises the fastening screw 55 which passes downwardly through the top jaw member to screw into the carrier block. When a single fastening screw 55 is employed the dowel pins 49 may be extended upwardly into the top jaw member to hold the carrier plate against rotative displacement.

90 The operation of the tool when used in applying corner ornaments to leather articles and the like is as follows:—

95 An article A upon which it is desired to secure a selected corner ornament C is disposed on the supporting plate 24 (after the corner ornament C has been loosely applied thereto) so that the same is aligned with and in front of the V-shaped forward end of the corner setting plate 29, whereupon the operator presses together the tool handles or lever members 17—18. The first effect of the manipulation of the tool handles is to 100 lower the clamp plate 50 into gripping relation to the article A so that the same is immovably held upon the supporting plate 24. As soon as the article A is thus clamped, continued movement of the jaw members 15—16 105 toward each other carries the cam-rods 35 downward so that their cam-portions 36 operatively engage and thrust forward the corner setting plate 29, whereby the forward end of the same thrusts the corner ornament C snugly home over the corner of the article A and thereupon holds the same subject to the operation of the punch plates 44—45 which descent upon the ornament so as to squeeze or pinch the same to cause the 110 prongs P with which it is provided (see Fig. 12) to penetrate the material of the article A to be thereby securely fastened to the latter. Inasmuch as the clamp plate 50 is yieldably supported the same will yield to 115 the continued movement of the jaw members, necessary to the operations above described, once it engages the article, as will be understood from an inspection of the drawings. The upper ends of the punch- 120

125

130

plates 44—45 will be caused to abut the overhanging portions of the keeper plate 48, whereupon operative downward pressure or thrust is imparted thereto when they encounter the corner ornament C to be secured.

It sometimes occurs that one side of a corner of an article will be thicker than the other side, due to pocket openings, etc., and consequently in order to properly 10 squeeze down an applied corner ornament it would be necessary that the punch plate over the thin side be projected further down than would be punch plate over the thick side. In order to provide for the 15 variations of position of either punch plate according to the circumstances I provide slideable shim plates 40, one cooperating with each punch plate and independently manipulatable. Each shim plate 40 has an upstanding finger-piece 40' and the keeper plate 48 is 20 provided with slots 48' to accommodate the movement of said finger pieces. The shim-plates 40 may be moved rearwardly to interpose portions of the same between the 25 upper ends of the punch plates and said keeper plate 48, so that the punch plates may be adjusted to pinch the corner ornaments on the thinner portions of an article when conditions so require.

30 From the above description it will be clear that the present invention furnishes a very handy tool for the character of work mentioned; the same being simple, compact and easy to operate.

35 It will be obvious that many variations in the specific structures described may be made without departing from the spirit of my invention, consequently said structures are to be taken as illustrative and not in a 40 limiting sense.

Having thus described my invention, I claim:—

1. In a hand tool of the kind described, 45 a pair of jaw members having pivoted handle members for moving the same toward and from each other, means connected with one jaw member for supporting an article and ornament to be secured thereto, means on the opposite jaw member for holding the article against displacement, cooperative means carried by said jaw-members for setting or holding the ornament in desired relation to the article, and plural punch 50 means also carried by said opposite jaw member and independently adjustable thereupon to engage and force said ornament into attached relation to the article.

2. In a hand tool of the kind described, 55 a pair of jaw members having pivoted handle members for moving the same in parallel relation toward and from each other, means connected with one jaw member for supporting an article and ornament to be secured thereto, means on the opposite jaw 60

member for holding the article against displacement, cooperative means carried by said jaw-members for setting and holding the ornament in desired relation to the article, punch means also carried by said opposite 70 jaw member to engage and force said ornament into attached relation to the article, and means to adjust said punch means for variations in thickness of the article to which said ornament is to be attached.

3. In a hand tool of the kind described, a bottom jaw member, a top jaw member, means to move said jaw members towards and from each other while maintained in parallel relation, a supporting plate connected with said bottom jaw member to support an article and ornament to be secured thereto, a yieldable clamp means connected with the top jaw member to hold the article against displacement from said supporting 80 plate, a setting plate slideable on said supporting plate to move and hold an ornament in assembled relation to the article, means carried by said top jaw member for operating said setting plate, and a pair of punch 85 plates also carried by said top jaw member for securing said ornament in attached assembled relation to said article.

4. In a hand tool of the kind described, a bottom jaw member, a top jaw member, pivoted handle members to move said jaw members toward and from each other while maintained in parallel relation, a supporting plate connected with said bottom jaw member to support an article and ornament to be secured thereto, a yieldable clamp 90 means connected with the top jaw member to hold the article against displacement from said supporting plate, a setting plate slideable on said supporting plate to move and hold an ornament in assembled relation to the article, cam-rods carried by said top jaw member to operate said setting plate, punch means also carried by said top jaw member for securing said ornament in attached 95 assembled relation to said article and means to adjust said punch means for variations in thickness of the article to which said ornament is to be attached.

5. In a hand tool of the kind described, a bottom jaw member, a top jaw member, pivoted, parallel motion handle members to move said jaw members toward and from each other, a supporting plate connected with said bottom jaw member to support an article and ornament to be secured thereto, a carrier means connected with said top jaw member, a clamp plate yieldably connected with the under side of said carrier means to hold the article against displacement from said supporting plate, a setting plate slideable on said supporting plate to move and hold an ornament in assembled relation to the article, cam means movable with said 110 carrier means to operate said setting plate, and a punch means carried by said top jaw member to engage and force said ornament into attached relation to the article.

6. In a hand tool of the kind described, a pair of jaw members having pivoted handle members for moving the same in parallel relation toward and from each other, means connected with one jaw member for supporting an article and ornament to be secured thereto, means on the opposite jaw member for holding the article against displacement, cooperative means carried by said jaw-members for setting or holding the ornament in desired relation to the article, and plural punch 120 means also carried by said opposite jaw member and independently adjustable thereupon to engage and force said ornament into attached relation to the article.

7. In a hand tool of the kind described, a pair of jaw members having pivoted handle members for moving the same in parallel relation toward and from each other, means connected with one jaw member for supporting an article and ornament to be secured thereto, means on the opposite jaw member for holding the article against displacement, cooperative means carried by said jaw-members for setting or holding the ornament in desired relation to the article, and plural punch 125 means also carried by said opposite jaw member and independently adjustable thereupon to engage and force said ornament into attached relation to the article.

- plate, and punch plates connected with said carrier means engageable with said assembled ornament to secure the same in attached relation to said article.
5. In a hand tool of the kind described, a bottom jaw member, a top jaw member pivoted handle members adapted to move said jaw members toward and from each other, a supporting plate connected with 10 said bottom jaw member to support an article and ornament to be secured thereto, a carrier means connected with said top jaw member, a clamp plate yieldably connected with the under side of said carrier means 15 to hold the article against displacement from said supporting plate, a setting plate slideable on said supporting plate to move and hold an ornament in assembled relation to the article, spaced cam-rods movable with 20 said top jaw member for operating said setting plate, punch plates connected with said carrier means engagable with said assembled ornament to secure the same in attached relation to said article, means to mount said 25 punch plates for individual limited vertical adjusting movement relative to said carrier means, said carrier means having abutments to back said punch plates, and shim plates slideably connected with said carrier means 30 for selective interposition between said punch plates and said abutments.
7. In a hand tool of the kind described, a bottom jaw member, a top jaw member, pivoted handle members adapted to move 35 said jaw members toward and from each other while retaining the same in parallel relation, a supporting plate connected with said bottom jaw member to support an article and ornament to be secured thereto, a 40 carrier block connected with said top jaw member, said carrier block having converging rear sides at right angles one to the other, a clamp plate to hold an article against displacement from said supporting 45 plate, and a pair of punch plates mounted respectively on the rear sides of said carrier block.
8. In a hand tool of the kind described, a bottom jaw member, a top jaw member, 50 pivoted handle members to move said jaw members toward and from each other, a supporting plate connected with said bottom jaw member to support an article and ornament to be secured thereto, a carrier 55 block connected with said top jaw member, said carrier block having converging rear sides at right angles one to the other, a clamp plate yieldably connected with the under side of said carrier block to hold 60 an article against displacement from said supporting plate, a pair of punch plates, means to mount said punch plates for individual limited vertical adjusting movement relative to said carrier block, said 65 carrier block having abutments to back
